United States Patent Office.

M. S. BRINGIER, OF ASCENSION PARISH, LOUISIANA.

Letters Patent No. 96,081, dated October 26, 1869.

IMPROVED APPARATUS FOR EVAPORATING CANE-JUICE.

The Schedule referred to in these Letters Patent and making part of the same.

To all whom it may concern:

Be it known that I, M. S. BRINGIER, of the parish of Ascension, State of Louisiana, have invented a certain new, useful, and improved Method of Evaporating Cane-Juice; and I do hereby declare the following to be a full, clear, and exact description of the same, as well as of my mechanical arrangements or agencies for carrying it into effect, reference being had to the annexed drawing, making a part of this specification.

The especial and primary object that is fulfilled by my invention, is to utilize the heat escaping from the furnace of the boilers in which the steam is generated that drives the engine of the sugar-mill, which is now wholly lost, by applying it to the evaporation of the cane-juice, and thus to dispense with the expensive additional furnace now employed by nearly every sugar-planter for such purpose, and to save the fuel required in connection therewith.

But there is a secondary, and, to some extent, a very important object that is accomplished by my invention, which is the application of the heat of all the waste steam, or of a certain portion of steam, designedly withdrawn from the boilers, to aid the process of evaporation, with the view, in both cases, to reduce, to the lowest possible limit, the cost of making sugar.

My invention also reduces the labor required to evaporate cane-juice, to a very considerable extent.

In order to apply the heat in question from the furnace of the mill and from the waste steam, or such portions of the steam from the boilers as may be withdrawn therefrom, and still leave enough to drive the machinery of the mill in the most effective manner, it is necessary to make the chimney of the mill of sheet-metal, instead of brick, to prevent the absorption and retention of any considerable portion of the heat by the walls thereof.

In fact, the best mode of applying my invention to practice, is to make the evaporating-pans in such form that they will themselves constitute sections of the chimney, and so as readily to be removable, should there be a need to repair them, or to get at them separately for any other reason.

But my invention will be better and far more quickly understood by an inspection of the drawing, which illustrates at once my method of applying the heat from the furnace of the boilers and the heat of the steam, which otherwise would be wasted, or which may be spared from the boilers of the mills, when the chimney is of rectangular form, and the pans constitute sections thereof.

The drawing exhibits three evaporating-pans A, B, C, fitted one above the other, and so made that there is a rectangular open space in the centre of them,

which, being connected with the furnace of the boilers, constitutes the chimney through which the products of combustion ascend, as in any ordinary case.

Across this open space or chimney any proper number of small pipes *a* pass through the opposite interior walls of each pan in one direction, so that each end of each of the said pipes communicates with the open spaces within said pans, and thus allows them to be filled with the juice whenever the pans are filled with it. The pipes of the different pans may all cross the chimney in one direction, or the pipes of one pan may cross those of the next pans to it at right angles, without affecting the operation of the invention in any appreciable degree, but I prefer to have the pipes all cross the chimney in the same or one direction.

These pipes establish, in connection with the interior faces *D* of the interior sides of the pans, which sides, as before stated, constitute the walls of the chimney, an extent of fire-surface which, being directly in the path and on the sides of the current of heat from the furnace up the chimney, I have found, by actual experiment, is sufficient to produce as rapid an evaporation as is compatible with good results in the manufacture of sugar.

The gas or steam from the pans may be thrown into the chimney through internal openings, as seen at *E*, in pan *C*, and thus increase the draught up the chimney, while at the same time adding to the quantum of heat concentrated therein, or it may be carried into the external air, by means of openings, as at *F*, as shown in pan *B*.

The auxiliary heat to which I have referred, as coming from the waste steam, &c., is applied by means of a system of internal pipes, *b*, as shown in pan *C*. These pipes are arranged within the pans so as to permeate the juice throughout most if not all portions of it, (for it is obvious that they may be adjusted and arranged in a variety of ways, all differing from the arrangement on the drawing,) and being connected with a pipe, *G*, so placed as to receive the steam as it escapes from the cylinder, at each stroke of its piston, and also, if need be, from a pipe leading directly from the boilers, they will obviously communicate a large part of the heat of the steam, as it passes through them, to the juice, and, hence, powerfully aid in its evaporation. The steam, after accomplishing its function, is returned again to the boilers, in condensed form, of course, there to be reconverted into steam, and so on indefinitely.

Any ordinary means, in the way of valves, may be employed to carry the juice, after it has been converted into sirup, from one pan to another, and to withdraw the sirup and sugar from the pans.

I have devised means for doing this in the most ef-

fective manner, but as they form no part of my invention, I do not, therefore, describe them herein, nor show them on the drawing.

I have demonstrated, by the actual practice of my invention, that the evaporation of any given quantity of juice can be effected by it at less than half the cost involved in the use of the ordinary arrangements for accomplishing the same object, and that the first cost of the organism, so to call it, is considerably less than that of an ordinary set of sugar-kettles or pans.

The three pans I have shown on the drawing, are to illustrate my invention, for I by no means confine myself to that or any given number, but reserve, on the contrary, in the most express terms, the right to extend the numbers indefinitely, and to vary the form in any manner I see fit, provided, always, I do not depart from the general principles herein set forth. I may even attach my pans in a permanent manner to walls of sheet or plate-iron chimneys, so that they will not be removable, and use an independent furnace in connection therewith, or with sectional pans, as shown on the drawing.

Having thus described my invention, What I claim, and desire to secure by Letters Patent, is—

1. Applying the heat from the furnace of the boilers of sugar-mills to the evaporation of cane-juice, when the same is done by the means of the pans C B A, and in the manner substantially as herein described, for the purpose set forth.

2. The arrangement of pipes *b* within evaporating pans, constructed, arranged, and operating as herein described, for the purpose set forth.

3. The pans A B C, when provided with pipes *a*, and otherwise constructed as herein described, in combination with the furnace of the sugar-mill, or an independent furnace, in lieu thereof, substantially as herein described, for the purpose set forth.

M. S. BRINGIER.
